UNITED STATES PATENT OFFICE.

JOSEPH J. PEELING, OF BROOKLYN, NEW YORK.

LOADING AND UNLOADING DEVICE.

1,266,851.

Specification of Letters Patent. Patented May 21, 1918.

Application filed January 22, 1916. Serial No. 73,712.

To all whom it may concern:

Be it known that I, JOSEPH J. PEELING, a citizen of the United States, residing at Brooklyn, in the county of Kings and State of New York, have invented certain new and useful Improvements in Loading and Unloading Devices, of which the following is a specification.

An object of my invention is to provide a loading and unloading device which is so constructed that it might be built as a part of a boat, car, or other carrier, comprising separate receptacles or holds which may be filled with grain, coal, gravel, or other like materials not of a perishable nature, means being provided to raise the independent holds or containers to an elevated position and the bottom thereof being so arranged that an outlet may be provided to permit the discharge of the contents.

A further object is to provide means by which the discharge openings of the compartment are closed and the closure thereof is maintained, and additional means for releasing this securing means and permitting control of the discharge of the contents of the containers.

A still further object is to provide means by which the containers are mounted against displacement to be held in the proper path of movement in both raising and lowering and means by which a chute may be mounted to have the contents of any one of the containers discharged therethrough.

With the above and other objects in view, my invention consists in certain novel features of construction and combinations of parts which will be hereinafter set forth in connection with the accompanying drawings and then more particularly pointed out in the claims.

In the drawings:

Figure 1 is a view in side elevation of the hull of a boat having my invention constructed in connection therewith and with parts broken away to more clearly illustrate the arrangement of the structure.

Fig. 2 is a top plan view of this disclosure in Fig. 1.

Fig. 3 is a transverse sectional view.

Fig. 4 is a sectional view of the lower end of one of the compartments with the bottom illustrated in the lowered position to permit the discharge of the contents of this receptacle.

55

Fig. 5 is a view in perspective to show the relative mounting of certain of the parts.

Fig. 6 is a view in elevation to show the operating mechanism.

Fig. 7 is an enlarged detail view to show the guiding means for the receptacles as the same are raised and lowered.

Fig. 8 is a detail view to better illustrate the means by which the chute is moved to and held in the operative relation.

65

In the present disclosure I have illustrated my invention as constructed as a part of a boat, and in this disclosure, the main hull 1 is made of such a size that the containers or compartments 2 fit therein, these compartments being received between the side walls and so mounted that they are positioned side to side to extend transversely across the hull, and it will of course be understood that these containers might be fitted in the hull throughout the entire length thereof when the boat or vessel is to be used as a barge or is to be towed, or where a power plant is used, the compartments would be mounted only in certain parts of the hull.

75

A frame structure comprising the angle beam uprights 3 and the cross bars 4 is

mounted on the hull in such a relation that the angle beam upright members 3 are positioned in a relation that as the compartments are raised from their mounting within the hull, they will be guided in their upward movement by these upright members 3. In some instances it may be found de-

85

sirable to use two L-shaped angle beams, and in other instances, it may be deemed desirable to use a single T-shaped angle beam, this arrangement of the parts being better shown in Fig. 7, however, it will be under-

95

stood that the primary object of these upright members 3 is to guide the raising and lowering movement of the compartments and to form a supporting structure for the rails 5 and 6 which are mounted on the side

90

100

bars 7 and 8 which are mounted on the uprights 3 in line with the sides of the hull 1 of the vessel.

A car 9 is mounted by the wheels 10 to be capable of movement along the extent of the tracks 5 and 6, and a winding drum 11 is carried by this car, in the present instance, being shown as mounted on the shaft of the hoisting motor 12. A dog 13 is provided 10 to work against teeth of the ratchet 14 and to normally permit turning movement of this winding drum 11 in one direction only, that being the direction in which it is driven by the motor 12. Cables 15 and 16 are led 15 over the pulleys or sheaves 17 and 18 to be connected with the winding drum 11 so that as the drum is turned under the impulse of the motor in the direction permitted by the ratchet and dog arrangement, these cables 20 will be wound onto the drum. Suitable cable securing eyes 19 and 20 are provided on the upper edges of the containers 2 and as the cables 15 and 16 are connected with these eyes and are each led over the drum 25 11, as the motor 12 is operated to rotate the drum 11, the cables will be equally taken in and in consequence the containers 2 will be raised to a position within the confines of the frame formed by the uprights 3 and 30 30 may be brought to a position with its bottom above the top of the hull of the vessel, the dog 13 engaging with the teeth of the ratchet wheel 14 to prevent back movement of the containers from the raised position. It is 35 not the intention that the car 9 shall be used as a traveling carrier, but rather that the car shall be positioned above one of the containers, and will then remain in the desired position to operate upon that container 40 and move the same in a predetermined vertical path, and thus the purpose of the tracks 5 and 6 is not to permit movement of the car while acting as a traveling crane, but rather to support and permit movement of 45 the car to the desired positioning above the predetermined compartment.

As is better shown in Figs. 3 and 4, the bottoms of the containers 2 are arranged in such a manner that they may be given movement to an inclined position where they form a chute and where the discharge opening is provided at that end of the bottom which is inclined downwardly, and also that they may be brought to the raised or closed 55 position and will be held in this position to retain the material which may be placed in the containers. The bottom 21 is mounted by the hinge 22 at the lower edge of one of the ends of the container 2, this hinge being 60 preferably in the nature of a piano hinge, and triangularly shaped side members 23 are connected with the side edges of this bottom portion 21 in a segmental formation to fit within the sides of the container so

that as the bottom 21 is lowered or swung 65 around its mounting by the hinge 22 to discharge the contents of the containers, these sides 23 will form a continuation of the sides of the containers and in consequence a substantially chute formation is provided at the 70 bottom of the container, with the opening at the inclined end of the bottom 21. A plate 24 is mounted across the top edges of these side members 23 to hold the same spaced the proper distance apart and the retaining 75 hooks 25 are connected at the upper edge of this plate 24 at points adjacent the ends thereof and are extended upwardly to have the hooked portion thereof received over the top edge of the end against which the plate 80 24 has bearing so that the bottom 21 will be held in the raised or closed relation. The eyes 26 are provided on the hook members 25 and the cables 27, referring now more particularly to Fig. 6, are provided to be 85 connected through these eyes 26 to be led up over the pulleys 28 and received around the winding drum 29 connected on the shaft of the hoisting motor 30, thus arranging the parts in such a manner that by exerting a 90 hoisting strain upon the cables 27, the hook members 25 will be raised sufficiently that the hooked portion thereof may be disengaged from the top edges of the ends of the containers and then by permitting the return of the cables over the pulleys 28, the bottoms may be lowered to give the proper inclination to the bottom 21 and to provide a discharge opening of the proper size 95 through which the contents of the containers 100 may pass out.

A grooved track 31 is mounted on the side of the hull 1, and a chute 32 has a hook plate 33 carried by the under side thereof to be engaged in this grooved track 31 so that 105 the chute may be secured in the proper position to receive the contents of any one of the containers as it may be discharged down over the inclined bottom 21 when the bottom has been moved to the position shown in the 110 upper part of Fig. 3, and also in Fig. 4, and it will of course be understood that this chute 32 may be extended to any length which may be desired. Where the device is constructed in conjunction with a vessel, it 115 is perhaps desirable that the deck plates 34 be hinged at one of the side top edges of the hull to be capable of being swung down over the open upper end of the containers 2, this arrangement of the parts being such 120 that as the deck plates or covers 34 are moved to the closed position, a continuous deck or floor is provided over the hull and as these covers are raised, they are entirely 125 out of the path of movement of the containers and the containers may be raised or lowered as desired.

While I have herein shown and described

the device of my invention as constructed in conjunction with a vessel, it will be understood that the same structure might be applied to the ordinary coal car or to any other carrier or vehicle, the purpose of the same being to permit the unloading of the load or cargo without manual handling and also to permit this unloading with the greatest speed, also it will be apparent that a carrier 5 constructed after this manner might be loaded with coal, grain, or other commodities by being moved or propelled beneath a chute from which the commodities to be handled are being discharged, this making 10 the several containers very readily filled, and further it will be seen that modifications and changes in the construction and arrangement of the parts other than those which have been hereinbefore suggested might be 15 resorted to without departing from the spirit and scope of my invention, and hence I do not wish to be limited to the exact disclosure but only to such points as may be set forth 20 in the claims.

25 I claim:

1. A loading and unloading device comprising a plurality of rectangularly shaped receptacles placed in a side-abutting relation, a frame carried above the positioning of 30 said containers and provided with members acting to guide said containers as the same are raised and lowered in a vertical path, a track carried by the supporting structure, a car mounted on said track, means carried 35 by the car to selectively raise and lower said containers, said containers having the bottoms thereof hinged to permit swinging movement to an inclined relation to discharge the contents of the containers, and 40 means for releasably holding said bottoms against swinging movement to the inclined position.

2. A loading and unloading device comprising a plurality of rectangularly shaped 45 receptacles placed in a side-abutting relation, a frame carried above the positioning of said containers and provided with members acting to guide said containers as the same are raised and lowered in a vertical 50 path, a track carried by the supporting structure, a car mounted on said track, means carried by the car to selectively raise and lower said containers, said containers having the bottoms thereof hinged to permit 55 swinging movement to an inclined relation to discharge the contents of the containers, means for holding releasably said bottoms against swinging movement to the inclined position, a chute to be positioned in line 60 with the inclined bottom, and means to hold the chute in the proper relation with respect to any one of the containers.

3. A loading and unloading device comprising a plurality of rectangularly shaped

receptacles placed in a side-abutting relation, a frame carried above the positioning of said containers and provided with members acting to guide said containers as the same are raised and lowered in a vertical path, a track carried by the supporting 65 structure, a car mounted on said track, means carried by the car to selectively raise and lower said containers, said containers having the bottoms thereof hinged to permit swinging movement to an inclined relation to discharge the contents of the containers, means for detachably holding said bottoms against swinging movement to the inclined position, means for limiting the swinging movement of said bottom, a chute 70 to be positioned in line with the inclined bottom, means to hold the chute in the proper relation with respect to any one of the containers, and a cover plate hinged adjacent each of said containers to be closed down 75 over the same when the container is in the lowered relation.

4. A loading and unloading device comprising a plurality of receptacles placed in abutting relation, a frame carried above said 80 receptacles and provided with a plurality of vertically extending guiding tracks for receiving said receptacles and guiding the same vertically in their upward movement, a track carried by said vertically extending 85 tracks, a carriage mounted upon said last mentioned track, and means engaging said receptacles and carried by said carriage for raising said receptacles to a dumping position. 90

5. A loading and unloading device comprising a plurality of receptacles placed in abutting relation, a frame carried above said receptacles, means for guiding said receptacles vertically upon said frame, a track 105 carried above the top of said frame, a car mounted upon said track, lifting cables secured to said receptacles, winding drums carried by said car, said cables wound upon said drums, a bottom hinged to each receptacle, a cable secured to said bottom and wound upon one of said drums, a pawl and ratchet mechanism carried by one of said drums for permitting said drums to be released and allowing said bottom to swing 110 to an open position, and means for limiting the swinging movement of said bottom. 115

6. A loading and unloading device comprising a receptacle, a frame supporting said receptacle, means for moving said receptacle vertically upon said frame, a track carried by the top of said receptacle, lifting cables secured to said receptacle, a car mounted upon said track, winding drums carried by said car and engaging said cables 120 for raising and lowering said receptacle, a bottom hinged to said receptacle, a guiding rod secured to said bottom and carried by 125

said receptacle, a cable engaging said guiding rod and wound upon one of said drums, a pawl and ratchet arrangement carried by said last mentioned drum, for releasing said 5 rod and permitting said bottom to swing to an open position, and said rod provided with an overhanging end adapted to engage a portion of said receptacle for limiting the

downward swinging movement of said bottom when said rod is released.

In testimony whereof I affix my signature in presence of two witnesses.

JOSEPH J. PEELING.
